CLAIM

The ornamental design for an "attendant module", as shown and described.

DESCRIPTION

FIG. 1 is a front, right perspective view of an example attendant module.

FIG. 2 is a front view of the attendant module of FIG. 1.

FIG. 3 is a rear view of the attendant module of FIG. 1.

FIG. 4 is left side view of the attendant module of FIG. 1.

FIG. 5 is a right side view of the attendant module of FIG. 1.

FIG. 6 is a top view of the attendant module of FIG. 1.

FIG. 7 is a bottom view of the attendant module of FIG. 1.

FIG. 8 is a front, right perspective view of an example attendant module.

FIG. 9 is a front view of the attendant module of FIG. 8.

FIG. 10 is a rear view of the attendant module of FIG. 8.

FIG. 11 is left side view of the attendant module of FIG. 8.

FIG. 12 is a right side view of the attendant module of FIG. 8.

FIG. 13 is a top view of the attendant module of FIG. 8; and, FIG. 14 is a bottom view of the attendant module of FIG. 8.
